US0D1109697S

(12) **United States Design Patent** (10) Patent No.: **US D1,109,697 S**
(45) Date of Patent: ** Jan. 20, 2026

(54) **VEHICLE-MOUNTED WIRELESS CHARGER**

(71) Applicant: **Weiyu (Shenzhen) Technology Co., Ltd.**, Shenzhen (CN)

(72) Inventor: **Jie Xiang**, Guangdong (CN)

(**) Term: **15 Years**

(21) Appl. No.: **35/523,765**

(22) Filed: **Dec. 13, 2024**

(80) **Hague Agreement Data**

Int. Filing Date: **Dec. 13, 2024**

Int. Reg. No.: **DM/243299**

Int. Reg. Date: **Dec. 13, 2024**

Int. Reg. Pub. Date: **Jan. 24, 2025**

(30) **Foreign Application Priority Data**

Dec. 5, 2024 (CN) 202430773830.2

(51) LOC (15) Cl. **13-02**

(52) U.S. Cl.

USPC **D13/108; D14/253**

Primary Examiner — Michelle E. Wilson

Assistant Examiner — Charles Hwang

(57) **CLAIM**

The ornamental design for a vehicle-mounted wireless charger as shown and described.

DESCRIPTION

1. Vehicle-mounted wireless charger

1.1 : Front

1.2 : Back

1.3 : Left

1.4 : Right

1.5 : Top

1.6 : Bottom

1.7 : Perspective

1.8 : Perspective

1.9 : Perspective

1.10 : Perspective

Reproduction 1.1 is a front view of a vehicle-mounted wireless charger showing my new design; reproduction 1.2 is a rear view thereof; reproduction 1.3 is a left view thereof; reproduction 1.4 is a right view thereof; reproduction 1.5 is a top view thereof; reproduction 1.6 is a bottom view thereof; reproduction 1.7 is a front, top and right side perspective view thereof; reproduction 1.8 is a rear, bottom and right perspective view thereof; reproduction 1.9 is a rear, top and right side perspective view thereof; and reproduction 1.10 is a rear, bottom and left side perspective view thereof.

1 Claim, 10 Drawing Sheets
